CLAIM

The ornamental design for a spinous process spacer, as shown and described herein.

DESCRIPTION

FIG. 1 is a top perspective view of a spinous process spacer showing our new design;

FIG. 2 is a side elevation thereof;

FIG. 3 is a side elevation of the side opposite that shown in FIG. 2;

FIG. 4 is a front elevation thereof;

FIG. 5 is a rear elevation thereof;

FIG. 6 is a top plan view thereof; and,

FIG. 7 is a bottom plan view thereof.

The broken lines shown in the drawings illustrate structure and form no part of the claimed design.
